his Attorney.

UNITED STATES PATENT OFFICE.

EDWARD SENN, OF CINCINNATI, OHIO.

AGRICULTURAL TOOL.

1,249,213.

Specification of Letters Patent. Patented Dec. 4, 1917.

Application filed August 11, 1916. Serial No. 114,393.

To all whom it may concern:

Be it known that I, EDWARD SENN, a citizen of the United States, residing at Cincinnati, in the county of Hamilton and State 5 of Ohio, have invented certain new and useful Improvements in Agricultural Tools, of which the following is a specification.

My invention relates to manually handled agricultural tools, such as hoes, rakes, and 10 the like, and is especially applicable to such tools formed up out of sheet metal.

It is one of the objects of my invention to provide strengthening means between the neck and body portions of the tool for distributing the stress upon the body-portion 15 over a large portion of its area, accomplished by providing the body-portion with a reinforcing depression adjacent to the neck-portion and extending lengthwise of the body-portion; further to connect the upper wall 20 of said reinforcing depression of the body-portion with the neck-portion by means of reinforcing bent-over edge-portions of the metal; and, further, to form the socket-portion 25 preferably tapering with the formed-up wings thereof overlapping each other and rigidly secured together at their edges.

The invention will be further readily understood from the following description and 30 claims, and from the drawing, in which latter:

Figure 1 is a plan view of a blank of sheet metal for forming the hoe.

Fig. 2 is a plan view of the same in partly 35 formed relation.

Fig. 3 is a perspective front elevation of a formed hoe.

Fig. 4 is an edge elevation of the same, with a handle secured in the socket-portion, 40 the handle being partly broken away.

Fig. 5 is a cross-section of the hoe, taken on the line 5—5 of Fig. 4, partly broken away.

Fig. 6 is a horizontal cross-section of the 45 same, taken on the line 6—6 of Fig. 4.

Fig. 7 is a vertical cross-section of the same, taken on the line 7—7 of Fig. 3.

Fig. 8 is a rear view of the formed hoe.

Fig. 9 is a plan view of a blank of sheet 50 metal for forming a rake.

Fig. 10 is a front perspective view of the formed rake; and,

Fig. 11 is a cross-section of the same on the line 11—11 of Fig. 10.

55 The blank 11 of sheet metal for forming the hoe comprises a body-part 12, wings 13,

14, and a connecting-part 15, slots 16, 17, being located between said respective wings and the body-part.

The wings taper inwardly, the outer ends 60 of the wings being wider than the inner ends of the wings. The wing 14 is wider than the wing 13 and is provided with off-set edges 18, 19. The upper edge of the blank between the wings is preferably formed with a comparatively shallow incision 20 for the purpose hereinafter to be described.

In the first operation for forming up the hoe, the body-part of the blank is provided with a forwardly pressed depression 25 for 70 forming the body-portion 26 of the hoe, the depression 25 being a reinforcing depression extending lengthwise of the width of the hoe to a greater extent than the width of the neck-portion 27 and of the socket-portion 75 28 of the completed hoe, in order to distribute the stress from the socket-portion through the neck-portion over a wide area of the body-portion of the hoe.

The connecting-part 15 is at the same operation provided with a reinforcing depression 29 which extends up and down across the neck-portion of the hoe when completed, and merges into the reinforcing depression 25 of the body-portion of the hoe and extends upwardly within the lower end of the bottom wall 30 of the socket of the socket-portion of the hoe. At the first operation, preferably also, the wings 13, 14, are bent forwardly and preferably slantingly edge-wise toward the front face of the hoe, as 85 shown in Fig. 2.

The wings are then formed curvingly, with opposite edges of the wings presented toward each other in overlapping arrangement, as exemplified in Fig. 3, the offset edges 18, 19, being connected with the body of the wing 14 by means of outward bends 31, for causing said offset edges to be received outside the coacting edges of the 100 wing 13, so that said offset edges shall lap the edges of the coacting wing for forming a socket, the inner face of which is round in cross section, the socket being a tapering socket, due to the tapering form of the 105 wings. The overlapping edges of the wings are rigidly connected together, as by suitably electrically welding the same together, as shown by the spot-welds 32.

The provision of the incision 20 enables 110 the forming of the wings into the socket-portion with a substantially flat bottom 30.

It will be noted from the blank shown in Fig. 1, that the connecting-part 15 of the blank is comparatively wide and of substantially greater width than the neck-portion 27 of the hoe after its formation. This extra metal enables me to provide lateral edge-portions 36 extending integrally from the respective sides of the neck, and upper edge-portions 37 extending integrally from the upper edge of the body-portion, which are respectively bent backwardly upon the body-part of the neck-portion, with a reverse bend 38, and upon the upper wall 39 of the reinforcing depression 25 of the body-portion, with a reverse bend 40, the upper ends of said lateral edge-portions 36 meeting and merging into the forward part of the bottom of the socket-portion, as shown at 41 in Fig. 3, whereby a lapped-over reinforcing edge extends from each side of the socket-portion across the neck-portion and laterally along the upper wall of the reinforcing depression 25 of the body-portion 26 of the device, whereby the strain from the handle of the hoe is distributed over a large area of the body-portion, the stress being received by the formed depressed part of the body-portion and distributed over said body-portion.

The tool end of the handle 45 is formed tapering, as shown at 46, in Fig. 4, for being received in the tapering socket, wherein it is secured, as by suitable brads 47 received through suitable holes in the wall of the socket-portion into the handle.

In Figs. 9, 10 and 11, I have illustrated my invention as applied to a rake, in which similar parts are shown by similar but primed reference numerals. The reinforcing depression 25' extends lengthwise along the upper bar 51 of the rake, to substantially the end walls 52 of the upper bar, the teeth being shown as formed up out of the sheet metal blank by providing the teeth with lengthwise reinforcing depressions 53, extending up and down, the upper ends of which merge into said cross depression 25'.

The application of my invention to other agricultural tools than those herein specifically shown and described will be readily seen, and the claims are intended to apply generally to said tools.

Having thus fully described my invention, what I claim as new and desire to secure by Letters Patent, is:

1. A tool of the character described formed out of sheet metal, comprising a body-portion, a socket-portion, and an intermediate neck-portion, said socket-portion comprising tapering wings tapering toward each other and the edges of which overlap and are welded together, and said sheet metal provided with reinforcing edges laid over upon said neck-portion and body-portion and connecting said socket-portion and body-portion.

2. A tool of the character described formed out of sheet metal, comprising a body-portion, a socket-portion and an intermediate neck-portion, said socket-portion formed out of wings whose edges overlap and are welded together, and reinforce layers at the sides of said neck-portion integrally connecting said socket-portion and said body-portion.

3. A tool of the character described formed out of sheet metal, comprising a body-portion, a socket-portion and a connecting neck-portion, said body-portion provided with a reinforcing depression at the upper part thereof, said reinforcing depression being wider than said socket-portion, the edges of the sheet metal at the sides of said neck-portion and above the upper wall of said reinforcing depression being bent over upon said neck-portion and said upper wall.

4. A tool of the character described, comprising a body-portion, a neck-portion and a socket-portion, said body-portion provided with a reinforcing depression extending lengthwise of said body-portion laterally to greater extent than said neck-portion and said socket-portion and having an upper wall, said neck-portion provided with a reinforcing depression extending up and down across said neck-portion and merging at its bottom into said first-named reinforcing depression, and the edge metal at the sides of said neck-portion and at said upper wall of said first-named reinforcing depression respectively reversely bent and laid over upon the sides of said neck-portion and upon said upper wall of said first-named reinforcing depression.

5. A tool of the character described, comprising a body-portion, a socket-portion and an intermediate neck-portion, said body-portion provided with a reinforcing depression of greater width than said neck-portion and said socket-portion and extending lengthwise of said body-portion, said neck-portion provided with a narrower reinforcing depression extending up and down across said neck-portion and at its upper end extending into said socket-portion and at its lower end merging into said wider reinforcing depression of said body portion, the lateral portions of the metal of said neck-portion and the upper edge of said body-portion reversely bent respectively upon said neck-portion and upon said upper edge of said body-portion forming reinforcing layers which at their lower ends extend laterally lengthwise of said first-named reinforcing depression, and said first-named reinforcing depression extending laterally outwardly beyond said reinforcing layers.

6. A tool of the character described formed out of a sheet metal blank having laterally extending wings, and comprising a body-portion, a socket-portion and a connecting neck-portion, said body-portion provided with a reinforcing depression at the upper end thereof, said reinforcing depression being wider than said socket-portion, said socket-portion formed by means of said 5 wings with the edges of said wings overlapping and welded together, the edges of the sheet-metal at the sides of said neck-portion and above the upper wall of said reinforcing depression bent over into the bottom of 10 said socket-portion, upon the sides of said neck-portion and upon said upper wall.
7. A tool of the character described, comprising a body-portion formed with teeth, a socket-portion and an intermediate neck-portion, said body-portion provided with a 15 reinforcing depression in its upper part ex-

tending lengthwise of said body-portion and having an upper wall, said neck-portion provided with a reinforcing depression extending up and down across said neck-portion and merging at its bottom into said first-named reinforcing depression, the edge metal at the sides of said neck-portion and at said upper wall respectively reversely bent and laid over upon the sides of said 25 neck-portion and upon said upper wall, and said teeth provided with reinforcing depressions extending up and down and at their upper ends merging into said first-named reinforcing depression. 30

In testimony whereof, I have hereunto signed my name in the presence of two subscribing witnesses.

EDWARD SENN.
